(57) **CLAIM**

The ornamental design for a measuring tool and/or toy replica thereof, as shown and described.

DESCRIPTION

FIG. 1 is a front-left isometric view of a first embodiment of a measuring tool and/or toy replica thereof, showing my design;

FIG. 2 is a bottom-right isometric view thereof;

FIG. 3 is a left side view thereof;

FIG. 4 is a right side view thereof;

FIG. 5 is a front view thereof;

FIG. 6 is a rear view thereof;

FIG. 7 is a top view thereof;

FIG. 8 is a bottom view thereof;

FIG. 9 is a bottom-right isometric view of a second embodiment of a measuring tool and/or toy replica thereof;

FIG. 10 is a front-left isometric view thereof;

FIG. 11 is a left side view thereof;

FIG. 12 is a right side view thereof;

FIG. 13 is a front view thereof;

FIG. 14 is a rear view thereof;

FIG. 15 is a top view thereof; and,

FIG. 16 is a bottom view thereof.

The broken lines throughout the Figures show portions of the measuring tool and/or toy replica thereof that form no part of the claimed design.
